(57) **CLAIM**

The ornamental design for a walker for disabled children, as
shown and described.

DESCRIPTION

FIG. 1 is a perspective left side view of a first embodiment
of a walker for disabled children showing my new and
ornamental design, the right side perspective view being a
mirror image; and,

FIG. 2 is a perspective left side view of a second embodiment
of a walker for disabled children showing my new and
ornamental design, the right side perspective view being a
mirror image.
